LADING STRAP ANCHOR

Joseph C. Abel, Westwood, N.J., assignor to ACF Industries, Incorporated, New York, N.Y., a corporation of New Jersey

Application December 20, 1957, Serial No. 704,067

10 Claims. (Cl. 105—369)

The present invention relates to lading strap anchors and refers more particularly to a type of such anchor mounted on a vertical framing post of a freight vehicle.

The modern box car and similar freight vehicles have side walls with metal framing posts, sheet metal exterior siding and wood board inner lining nailed to furring strips bolted to the framing. Lading straps in common use can transmit forces of up to 9,000 lbs., and it is therefore desirable to have the strap anchors at least equally strong. It is further desirable to have a large number of anchors in the vehicle for convenience in lashing the freight and in order to distribute the load.

An object of the present invention is to provide a very strong strap anchor.

Another object is to provide an anchor at small cost, so that a vehicle may be provided economically with an adequate number of anchors.

Another object is to provide an anchor which is very easy to build into new vehicles and of the above described type and which may also be built into existing cars at reasonable expense.

In accomplishing the objects of the present invention, an anchor is provided in two parts. A flange of a framing post adjacent and parallel to the inner lining is formed with an upper and a lower slot. The anchor is U shaped with a vertical, straight bight and legs which enter the slots of the post. The legs have downwardly extending lugs at their outer ends, and shoulders spaced from and facing the lugs. The strap guide is a dished metal body having a front surface flush with the inner lining when the rear surface of the guide is against the post. The guide is the same height as the anchor exclusive of the lugs, and has slots extending inwardly from its top and bottom boundary. The legs of the anchor enter the slots of the guide and of the post and the lugs pass through them. The anchor and guide are moved downwardly together hooking the lugs into the post and the shoulders holding guide against the post. The guide is the height of a board of the inner lining and a short length of one board is removed to make room for it. When the board above the guide is put in place the assembly is secured against removal, the board being in contact with the anchor and guide and preventing upward movement of either.

These and other objects of the invention will be apparent to those skilled in the art from a study of the following description taken with the accompanying drawings in which:

Figure 1 is a perspective view of a box car interior embodying the present invention.

Fig. 2 is a front elevation of an enlarged fragment of said interior comprising the anchor and guide, partly broken away.

Fig. 3 is a section on the line 3—3 of Fig. 2.

Fig. 4 is a section on the line 4—4 of Fig. 2.

Referring now in detail to the drawings, the vehicle 10 is provided with a plurality of conventional angle iron framing posts 11 from which are supported in any desired manner the outer sheeting and furring strips, not shown,

2

and the inner lining constituted of horizontally extending tongue and groove wooden boards 12. A flange 13 of post 11 extends parallel and in contact with the boards 12 of the inner lining and is formed with the two vertically aligned slots 14.

The anchor member 15 is a U shaped bar, having a long, straight, vertically extending bight portion 16 and legs 17 terminating in downwardly extending terminal lugs 18. Legs 17 are formed with the shoulders 19 facing outwardly, that is, towards their free ends.

The strap guide 20 is a dished body of metal having a forward or rim portion 21 extending substantially flush with the exposed surface of the boards 12 of the inner lining and spaced from the flange 13 of post 11. A rear portion 22 of guide 20 is in contact with flange 13, and the web portion 23 is intermediate the portions 21, 22 and merges with both. Rear portion 22 is formed with the two slots 24 extending perpendicularly inwardly from its top and bottom boundaries respectively. The legs 17 extend through slots 24 and the shoulders 19 abut the portion 22 and thus hold guide 20 against flange 13. Guide 20 is substantially as high as the anchor 15 exclusive of the lugs 18 and extends on both sides of anchor 15 to guide the strap under the bight 16 in known manner.

The anchor 15 is first assembled with the guide 20 by entering the upper leg 17 into the upper slot 24 until the limit of entry is reached when shoulder 19 abuts the portion 22, then pivoting the guide 20 into the illustrated position as indicated by the curved arrow 25. A small tack weld 26 may then be applied to maintain the anchor and guide as a sub assembly.

The holes 14 are of a size to pass the legs 17 and lugs 18 and the legs 17 are entered in the holes 14 and the lugs 18 pass through the holes 14. The anchor and guide 35 are then moved downwardly, the lugs 18 thereby hooking the assembly fast to flange 13. The assembly may not be removed except by upward movement relative to post 11 and this may be prevented in either of two ways. Another small weld 27 may be applied to upper leg 17 and flange 13, however this is optional. Whether or not the weld 27 is applied, a board 12A will now be put in place above the assembly 15, 20, contacting both the anchor 15 and guide 20 and being thus permanently interposed in the path of upward movement of the anchor and guide, 40 thereby locking them in position. The other boards 12 are fitted around the anchor and guide in known manner, providing an interior wall surface in the vehicle devoid of crevices or open seams in which grain or other perishable freight could collect.

An anchor and guide is thus provided, of extreme simplicity and strength, and which transmits the pull of the lading strap directly to the framing post 11.

The invention may be modified in various aspects as will occur to those skilled in the art and the exclusive use of all modifications as come within the scope of the appended claims is contemplated.

What is claimed is:

1. A lading strap anchor arrangement for a freight vehicle, said vehicle comprising walls embodying vertical posts, said anchor arrangement comprising a bar of U shape, said bar comprising at the outer end of one leg a lug projecting therefrom toward the other leg and at the outer end of the other leg a lug projecting therefrom in the same direction as the first lug, a post of said vehicle being formed with two holes shaped to pass said legs and lugs, whereby upon passage of said lugs through said holes and by subsequent movement of said bar in the direction of projection of said lugs, said bar is locked against withdrawal from said post except after reversal of said last mentioned movement, and means connected to said post and permanently interposed in the path of said reverse movement.

2. A lading strap anchor arrangement for a freight vehicle, said vehicle having a wall embodying a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post, and means connected to said post and permanently interposed in the path of said upward movement.

3. A lading strap anchor arrangement for a freight vehicle, said vehicle having a wall embodying a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post and means permanently interposed in the path of said upward movement, each of said legs further having a shoulder facing the free end of said leg and limiting the extent of entry of said leg into the hole.

4. A lading strap anchor arrangement for a freight vehicle, said vehicle having a wall embodying a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post and means permanently interposed in the path of said upward movement, each of said legs further having a shoulder facing the free end of said leg and limiting the extent of entry of said leg into the hole, said arrangement further comprising strap guide means, said guide means comprising a dished body having a rear portion in contact with said post, a rim portion in spaced relation to said post and a web portion intermediate said two portions and merging into both, said guide means having a height substantially equal to said bar exclusive of said lugs and further being formed with a slot the height of each said leg and extending into said guide means from the top and bottom boundary thereof respectively, said legs further extending through said slots and said shoulders further holding said rear portion in contact with said post.

5. A lading strap anchor arrangement for a freight vehicle, said vehicle having a wall embodying a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post and means permanently interposed in the path of said upward movement, each of said legs further having a shoulder facing the end

of said leg and limiting the extent of entry of said leg into the hole, said arrangement further comprising strap guide means, said guide means comprising a dished body formed with holes and said legs extending through said holes, said body extending on both sides of said bar and for the full height thereof and being held in contact with said post by abutment with said shoulders.

6. A lading strap anchor arrangement for a freight vehicle, said vehicle having a wall embodying a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post, and said wall further embodying a multiplicity of horizontally extending boards constituting an inner lining, one of said boards extending across the top of said bar and in contact therewith and preventing said upward movement.

7. A lading strap anchor arrangement for a freight vehicle, said vehicle having a wall embodying a vertical post and wooden boards, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post, each of said legs further having a shoulder facing the end of said leg and limiting the extent of entry of said leg into the hole, said arrangement further comprising strap guide means, said guide means comprising a dished body formed with holes and said legs extending through said holes, said body extending on both sides of said bar and for the full height thereof and being held in contact with said post by abutment with said shoulders, one of said boards being permanently positioned in said wall above said bar and body and in contact with both and thereby locking said bar in said post.

8. A lading strap anchor arrangement for a freight vehicle, said vehicle having a wall embodying an inner lining of horizontally extending boards and a vertical post, said anchor arrangement comprising a substantially U shaped bar, the bight portion of said bar extending substantially vertically between an upper and a lower leg and each of said legs having at its outer end a downward extending lug, said post further being formed with a pair of holes, each hole being shaped to pass one of said legs and the associated lug, whereby upon passage of said lugs through said holes and downward movement of said bar relative to said post said bar is locked in said holes and may not be withdrawn except after upward movement relative to said post, each of said legs further having a shoulder facing the free end of said leg and limiting the extent of entry of said leg into the hole, said arrangement further comprising strap guide means, said guide means comprising a dished body having a rear portion in spaced relation to said post, a rim portion flush with the exposed surface of said inner lining, said body further comprising a web portion intermediate said two portions and merging into both, said guide means having a height substantially equal to said bar exclusive of said lugs and further being formed with a slot the height of each said leg and extending into said guide means from the top and bottom boundary thereof respectively, said legs further extending through

said slots and said shoulders further holding said rear portion in contact with said post and a board of said inner lining being permanently positioned in said wall above said bar and body and in contact with both and thereby locking said bar in said post.

9. A strap anchor construction for a freight vehicle of the type comprising a wall embodying an inner lining of horizontally extending boards and a metal framing post having a flange in parallel contact with said boards, said construction comprising an anchor and a strap guide, said anchor being U shaped and having a long, straight bight and legs having downturned terminal portions and outward facing shoulders, said strap guide being a slotted and dished body having a rear portion in contact with said flange, an intermediate web portion and a rim portion flush with said inner lining, said post being slotted and said legs of said anchor extending through the slots of said guide and of said post, said downturned portions of said legs extending below said slots of said post and locking said anchor in said post, said shoulders holding said guide against said flange and one of said boards of said lining extending above and in contact with said

5

anchor and guide and preventing unlocking of said anchor.

10. A lading strap anchor for mounting on the framing of a freight vehicle and within a wall inner lining thereof comprising a U-shaped anchor and a strap guide, said U-shaped anchor having a long straight bight and legs with outward facing shoulders and turned terminal portions, said strap guide having a slotted dished body with a rear portion for contact with the framing an intermediate web portion and a rim portion for flush alignment with the inner lining, said legs extending through the slots of said guide, said shoulders abutting said guide, said U-shaped anchor and said guide being secured together as a sub-assembly.
